UNITED STATES PATENT OFFICE.

JAMES B. STEEDMAN, OF LOUISVILLE, KENTUCKY, ASSIGNOR OF ONE-THIRD TO JOHN C. COX AND ONE-THIRD TO LOUIS SUMMERS, BOTH OF LOUISVILLE, KENTUCKY.

RAZOR-SHARPENER.

1,255,656.

Specification of Letters Patent.

Patented Feb. 5, 1918.

Application filed March 16, 1916. Serial No. 84,704.

To all whom it may concern:

Be it known that I, JAMES B. STEEDMAN, a citizen of the United States, residing at Louisville, in the county of Jefferson and State of Kentucky, have invented certain new and useful Improvements in Razor-
Sharpeners, of which the following is a full, clear, and exact description, reference being had to the accompanying drawings, forming part of the specification, and to the figures and letters of reference thereon.

This invention relates to razor honing and stropping machines and has as its object to provide a machine of this class simple in construction and capable of ready manipulation by any inexperienced person for the purpose of properly and accurately honing and stropping a razor.

Another aim of the invention is to so construct the machine that in the operation thereof the cutting edge of the razor will be uniformly sharpened and beveled throughout its entire length, thereby increasing the efficiency of the instrument and obviating the frequent resetting of the edge which is necessary if the razor is honed and stropped by hand by an inexperienced person.

Another aim of the invention is to so construct the machine that the razor blade will bear with uniform pressure upon the hone or strop in the operation of the machine and without the necessity of the user of the machine making frequent adjustments to secure this result.

Another aim of the invention is to so construct the machine that by the mere use of auxiliary holders the machine may be employed in the sharpening of all types of razor blades.

40 In the accompanying drawings:

Figure 1 is a top plan view of the machine embodying the present invention.

Fig. 2 is a vertical longitudinal sectional view therethrough.

45 Fig. 3 is a vertical front to rear sectional view taken in a plane with the axis of the shaft which supports the blade holder.

Fig. 4 is a group perspective view of the carrier for the said shaft and the means provided for tripping or reversing the shaft at the end of each stroke of the carrier.

Fig. 5 is a plan view of the razor blade holder removed from the machine.

55 Fig. 6 is a perspective view of the trip device in the position which it occupies when

the machine is to be employed for the purpose of honing a razor blade.

Fig. 7 is a similar view illustrating the position which the said device occupies when the machine is employed for the purpose of stropping a razor blade.

In the drawings the base of the machine is indicated by the reference character *a* and the said base is preferably of metal and at one side is provided with a section recessed 65 in its upper surface to interchangeably receive members *b*, one having a stropping surface and the other a honing surface. As these members may be of any suitable construction the drawings illustrate only one of 70 the said members, which is in the nature of a hone. The shaft which supports the razor blade holder and through the medium of which the holder is reciprocated, reversed, and at the proper times moved laterally over 75 the face of the hone or strop, is mounted in a suitable carrier in the nature of a block *c* provided with a handle *d* which may be grasped for the purpose of reciprocating the said carrier, the carrier block being constructed on its under side to work in a slot *e* formed in the base *a* and the said block being provided upon its said under side with a plate *f* which serves as a means for holding the block against separation from the 80 base.

The shaft above referred to is indicated by the reference character *f* and is provided at one end and more specifically its end which is located next adjacent the recessed 90 side of the base, with spaced circumscribing shoulders *h*. A guide *g* is mounted upon the base and this guide is longitudinally curved and has its concave side presented toward the recessed side of the base and its upper 95 edge extending beneath the shaft *f* and between the said shoulders. The shaft *f* is not only rotatable within the carrier block *c* but it is also longitudinally slidable in the said block and consequently as the carrier block is moved back and forth in the slot *e* the shoulders will coat with the guide in such manner that the shaft will be reciprocated in the carrier as well as bodily reciprocated longitudinally of the base with the 100 carrier. The shaft is provided at that end opposite the end at which the shoulders *h* are located, with a plurality of radial pins which are relatively displaced in the direction of length of the said shaft, these pins being 105 110

indicated by the reference character *p* and being here illustrated as three in number. The pins are designed for coöperation with the trip device heretofore mentioned, which 5 trip device includes brackets *l* secured by screws *n* to the upper side of the frame *a* and a plate *i* which is provided at its ends with ears pivotally mounted as at *m* upon the said brackets. Upon one face and at its 10 opposite ends, the plate *i* is provided with tripping fingers *q* having stepped shoulders for the successive coöperation therewith of the pins *p*. By reference to Figs. 6 and 7 of the drawings it will be observed that the 15 tripper plate *i* may be swung upon the pivots *m* to assume the position shown in Fig. 6, in which position the machine is adapted for the honing of a razor blade, or to assume the position shown in Fig. 7, in which position 20 of the tripper plate the machine is adapted for the stropping of a razor blade. In the first instance, that is to say in honing the blade, the blade is moved edge first over the surface of the hone and is automatically reversed at the end of each stroke of the carrier block, and in the second instance, or, in 25 other words, in stropping the blade, the blade is caused to move back first over the stropping surface and is automatically reversed at the end of each stroke of the carrier block.

The reference letter *a* indicates the blade holder into which the razor blade *v* is inserted and this holder is provided with a 30 stem which is fitted into the shaft *f* and is provided with a notched end *u* which straddles one of the pins *p* which pin at its inner end extends into the hollow shaft. In this manner the stem of the holder is connected 35 for rotation with the shaft and yet the stem may be readily withdrawn from the shaft when desired. Fixed upon the stem of the holder is a cam *t* the outline of which is clearly shown in Fig. 2 of the drawings and 40 this cam is designed to ride beneath a presser plate *w* which is provided at each end with an upstanding rod or stem *k* which fits slidably through the bore of a sleeve nut *z* adjustably threaded through a bridge member *j* secured by means of screws *a'* upon 45 the base of the machine. Springs *x* are mounted upon the stems *k* and bear at their lower ends upon the upper side of the presser plate and at their upper ends against the 50 lower ends of the said sleeve nuts, and it will be understood that while the plate may move upwardly against the tension of the springs, the stems *k* have free sliding movement through the respective nuts, and the 55 tension of the springs *x* may be varied by adjusting the said nuts so that the presser plate may be caused to bear more or less firmly upon the cam *t*. At their upper ends, the stems *k* project through guard members 60 secured upon the bridge member *j* and 65

these guard members protect the sleeve nuts *z* and prevent accidental disturbance of their adjustment.

The operation of the machine is as follows: A hone is first placed in the recess in 70 the base of the machine and the tripper device is adjusted to the position shown in Fig. 6, after which the razor blade is fitted into the blade holder and the holder is inserted into the hollow shaft *f*. The handle *d* is then 75 grasped and the carrier block is reciprocated lengthwise of the machine. At the end of each stroke of the block the shaft is reversely rotated to approximately a half turn and the razor blade holder is correspondingly turned 80 or reversed, this reversal being accomplished through the successive engagement of the pins *p* with the stepped shoulders of the trip fingers. In the reciprocatory motion of the 85 carrier block the shoulders *h* will coat with the guide *z* to cause reciprocatory motion of the shaft through the said carrier block and consequently the razor blade will be moved not only longitudinally of the hone but also across the said hone laterally. The 90 razor blade is held in contact with the surface of the hone through the downward pressure exerted by the presser plate *w* upon the cam *t* and this pressure may be regulated by adjusting the sleeve nuts *z*. 95

In adapting the machine for use in stropping a razor blade, a strop is substituted for the hone and the razor blade holder is withdrawn, reversed, and then reassembled with the shaft *f*, the tripper device being also reversed so as to assume the position shown in 100 Fig. 7 of the drawings.

Having thus described the invention, what is claimed as new is:

1. In a machine of the class described, a 105 support, an abrading element mounted thereon, a member mounted upon the support for reciprocation beside the said element, a shaft mounted upon the said member, a blade holder carried by the shaft, a series 110 of pins carried by the shaft and radiating therefrom and relatively displaced, and spaced trip members having stepped shoulders for engagement by the said pins at the ends of the strokes of the said member whereby to impart rotary motion to the 115 blade holder at the termination of each stroke.

2. In a machine of the class described, a 120 support, a member mounted upon the support for reciprocation, a shaft rotatably and slidably mounted upon the member, means for imparting sliding motion to the shaft upon reciprocation of the said member, 125 spaced tripping members each having a series of tripping shoulders arranged in stepped relation, the said tripping members being arranged in the path of movement of one end of the shaft when the first-mentioned member is reciprocated, a blade 130

holder carried by the shaft, and radial pins projecting from the said end of the shaft for engagement with the shoulders of the said tripping members whereby to reverse the shaft at the ends of the strokes of the first-mentioned member.

3. In a machine of the class described, a support, a member mounted upon the support for reciprocation, a shaft rotatably and slidably mounted upon the member, means for imparting sliding motion to the shaft upon reciprocation of the said member, spaced tripping members each having a series of tripping shoulders arranged in stepped relation, the said tripping members being arranged in the path of movement of one end of the shaft when the first-mentioned member is reciprocated, a blade holder carried by the shaft, radial pins projecting from the said end of the shaft for engagement with the shoulders of the said tripping members whereby to reverse the shaft at the ends of the strokes of the first-mentioned member, and means supporting the said tripping members for reversal whereby to position the same selectively above and below the plane of the said shaft.

4. In a machine of the class described, a support, an abrading member mounted thereon, a blade holder mounted for reciprocation upon the support beside the abrading element, the said blade holder being

rotatable, a cam element carried by the blade holder, and a yieldably supported presser plate extending longitudinally above the support and coacting with the cam element in a manner tending to rotate the blade holder whereby to yieldably hold the same in position to maintain the edge of a blade carried thereby in contact with the abrading element.

5. In a machine of the class described, a support, an abrading element mounted thereon, a rotatably supported blade holder mounted for reciprocation beside the said element, a presser plate extending longitudinally above the said support, a cam element upon the blade holder engaging the underside of the said presser plate, the downward pressure exerted by the presser plate upon the cam element serving to yieldably hold the blade holder in position with the edge of a blade carried thereby in contact with the abrading element, a spring exerting downward pressure upon the presser plate, and means for adjusting the tension of the said spring.

In testimony whereof, I have hereunto set my hand in the presence of two subscribing witnesses.

JAMES B. STEEDMAN.
